SIPHONPROOF FLUSHOMETER AND
BOWL COMBINATION

Cesare C. Campus, Santa Monica, Calif.

Application May 14, 1934, Serial No. 725,438

23 Claims.

(Cl. 4—70)

This invention relates to a siphon-proof flushometer, equipped with a $\frac{1}{2}$ " inlet for the water supply, in combination with a closet bowl; this arrangement is broadly new. This flushometer 5 in order to positively prevent back-siphoning, is provided with an air inlet equal to the internal diameter of the supply pipeline, without being provided with a check-valve or mechanism of movable parts, to prevent the spilling of water 10 through said air inlet; this also is broadly new. The spilling of water through said inlet is prevented by providing the passage for the flushing water into the water closet of suitable size as to prevent the water from overflowing through said 15 air inlet, and the rim of the bowl is also provided with means to prevent stagnant water from remaining therein.

Another characteristic is that when the piston valve is seated, no metal parts contact with one 20 another, thus eliminating the possibility of their sticking, which would prevent the valve from working. Also, as the valve is not rigidly guided, it has a chance to adapt itself on the seat, thus taking care of any imperfection of any of the 25 other members, thus leakage is eliminated, even at a very low water pressure.

The danger of back-siphoning cannot be positively eliminated by the use of a check valve, or mechanism provided with movable parts.

30 Check valves are the mechanism most used to prevent back-siphoning, as they allow the air to enter the supply pipeline, in order to break the vacuum, when it occurs therein, and to prevent the water from spilling through the air inlet at the time the valve is operated. Of course these two described functions will be satisfactorily performed, as long as the said check valve is in good order. It must also be considered that the size of the air inlet in the flushometers at 35 present in use, is indeed too small to be considered practical for the intended purpose, and especially when the safety of public health depends on such an unreliable device, as above described.

40 All flushometers are too noisy to be practical for private dwellings, but, when they are installed in private homes, in order to eliminate this inconvenience, the water is throttled by the water supply control valve; but this method is satisfactory only as long as the pressure in the main water supply does not drop to a point where the flushing of the bowl cannot be achieved, unless the control valve is regulated accordingly.

The object of my invention is to eliminate all of 55 the above described inconveniences.

In all forms embodying my invention, the principal elements and results are:

(a) The shell of the flushometer is provided with an air inlet of the same area as that of 60 the inside diameter of the supply pipeline, work-

ing in combination with the passages in the water closet, of suitable size to prevent spilling of water from the said air inlet without the help of a check-valve or movable part.

(b) Positive elimination of back-siphoning, as 5 no mechanism is necessary to control the air inlet of the flushing valve.

(c) Elimination of noise, due to the fact that the scouring and the refilling water enter the bowl at an exceedingly low pressure; the flushing 10 jet also works at a reasonably low pressure, which was practically proven, when my invention was reduced to practice about two years ago, and again improved about a year ago, and still further improved a few months ago, and tested in 15 my home in Santa Monica, where the maximum static pressure is about 65 lbs. The following Tables A and B show the working pressure of the jet under different pressures, which were regulated by a Mueller regulator valve, $\frac{1}{2}$ " size. 20

The experiment described in Table A was made with a siphon jet nozzle of $\frac{1}{4}$ " internal diameter, and the experiment described in Table B was made with a siphon jet nozzle of $\frac{3}{8}$ " internal diameter. 25

Internal diameter of the siphon jet nozzle $\frac{1}{4}$ "

Table B shows that from 40 lbs. to 60 lbs. the working pressure of the jet remained constant 60

at 22 lbs. and started to rise again at 65. Evidently the constant working pressure from 40 lbs. to 60 lbs. was due to the fact that although the pressure in the pipeline was increased, the passage in the nozzle was large enough to prevent a gradual increase of the pressure, but as soon as the pressure in the pipeline reached 65 lbs. the working pressure of the siphon jet started to increase again, showing that the passage of 10 the nozzle was not large enough to take care of the volume of water at 65 lbs. pressure, supplied through a $\frac{1}{2}$ " standard supply pipeline, about 57 feet long.

Table (A) shows no constant pressure in any 15 of the experiments, but a gradual increased pressure, due to the small sized internal diameter of the jet. Table (A) also shows that the water supply at 60 lbs. produced a jet of 44 lbs. working pressure, whereas table (B) shows that 60 lbs. 20 water supply pressure produces a jet of 22 lbs.— exactly hundred per cent less, due to the larger internal diameter of the nozzle.

Table (B) shows a 9 lbs. working pressure of the jet, which flushed the bowl most efficiently; 25 in fact, more than 2 lbs. of pea gravel were put into the bowl, covering the inlet of the trap, (about one inch above) also a rag 15" x 10", about $\frac{1}{8}$ " thick, 24 matches and two ounces of blueing; all of the above was completely flushed 30 at one flushing.

A second experiment was made by raising the working pressure of the jet to 22 lbs. The result was most surprising; in fact 60 feet of toilet paper was flushed at once; in another experiment 35 20 lbs. of pea gravel covering the entrance of the trap more than three inches, were also flushed completely, and finally in another experiment, 250 ordinary wooden household matches, 2 $\frac{1}{2}$ " long and $\frac{1}{8}$ " thick were completely flushed 40 out. This is a convincing result that a nozzle of larger internal diameter is preferable, because of its efficiency and because of the constant working pressure resulting from 40 lbs. to 60 lbs. as shown in Table (B).

45 It is understood that the jet could not be made much larger than $\frac{3}{2}$ " when a 1.2" standard supply pipeline is used, therefore, the internal diameter of the jet nozzle is subordinate to the diameter of the supply pipeline and the pressure 50 therein.

The other features and advantages of the valve will be further on described.

This method of flushing a bowl in three different operations is not broadly new, as the 55 following patents show: F. H. Paradice, Patent No. 666,152, Jan. 15, 1901; W. Scott, Patent No. 796,458, Aug. 8, 1905; W. C. Groeninger, Patent No. 1,896,950, Feb. 7, 1933; but in my case, although 60 my invention is not broadly new, it is substantially different.

The Scott apparatus is provided with a nozzle, projecting the water parallel to the upper leg of the trap, impinging against the wall of the downward leg of said trap; the size of the orifice of the jet could not be less than $\frac{5}{8}$ ", as that of all 65 other bowls at present in use. In my case the orifice of the jet is much smaller, namely about $\frac{3}{2}$ " and a smaller jet of $\frac{1}{4}$ " was extensively described in my Patent 1,928,717, issued October 70 3, 1933. In my case, the jet projects against the wall of the upper leg of the trap, but below the level of the sealing water; the angle of the jet varies according to the type of bowl, but to obtain a satisfactory flushing, the jet must always 75 impinge against the wall of the upper leg of the

trap and below the level of the sealing water. In my present invention, the jet projects in a downward direction, impinging against the bottom wall of the orifice of the trap; this arrangement is necessary when a wash-down bowl is used. Scott valve will never flush with a $\frac{1}{2}$ " water supply.

The conduit of the water supply to the jet in the Scott apparatus is not equipped with a jet control valve, independent from the main control valve of the water supply. The Scott apparatus is a blow-out, and very noisy type of bowl, which does not require siphon action of flushing; in fact the trap shown in Fig. 1 does not show any choke, as is usually required to obtain a siphonic action; my bowl flushes by siphon 15 action and the passages in the rim are of suitable size to prevent spilling of water through the flushometer air inlet, thus working in combination.

The Scott apparatus has no mechanism to prevent back-siphoning. In flushing valves of the three-cycle type it is to be noted that the valve does not dispose of the entire volume of water at one time to flush the bowl, as in the case of the ordinary flush valve working in combination 25 with the ordinary bowl, but in the three-cycle type the entire volume is divided into about three equal parts, which consecutively discharge into the bowl. Therefore, it is not necessary to have the area of the orifices discharging into the bowl 30 as large as if the entire volume of water were being disposed of at one time. Nevertheless, back-building of the water is readily prevented.

Experiments and calculations with reference 35 to the area of the discharge orifice into the bowl have been made with the following results:

The discharge end of the valve has been connected to the bowl and the inlet to a main supply with a half-inch standard pipe forty feet long with the water pressure in the main as high 40 as one hundred pounds, which pressure is rarely, if ever, encountered in municipal supply systems as used today. By having the conduit area of the orifices from which the water discharges into the bowl, namely, the perforations under 45 the rim and the jet orifices, approximately ten times larger than the area of the internal diameter of the supply pipe, operation of the valve causes no leakage or overflow to occur through the unobstructed air inlet of the valve casing, 50 showing that no back-building is present. It is unnecessary to consider a pressure higher than one hundred pounds as this is very seldom, if ever, encountered, because of the fact that the fixtures are not built to withstand any such 55 pressure.

It will be seen from the foregoing that in view of the fact that a three-cycle flush valve dispenses only one-third of the total volume of water at a time, it is unnecessary to increase the total area of the orifices greatly from that present in standard bowls of present day use. In the ordinary so-called wash-down bowl as known today, and which is probably most in use, the area of the orifices discharging into the bowl 60 is approximately seven and one-half times larger than the area of the internal diameter of a one-half inch supply pipe line, which area is represented by twenty-eight perforations of substantially one-fourth inch diameter. By adding 65 ten more perforations of the same diameter the total area is increased to a total ratio of 1 to 10. This operation will take care of back-building of the water with a pressure up to one hundred 70 pounds. It is to be understood that this phase 75

of the invention is not necessarily limited to a half-inch supply pipe line, but that regardless of the size of the supply pipe line if the ratio of 1:10 is maintained no backbuilding will take place.

5 The Scott apparatus is provided with a piston valve, a sleeve valve and a stationary piston valve projecting into the center of said sleeve, practically the Scott flushometer is equipped with three valves. In my case, an ordinary piston valve is used, which mechanism has no similarity whatsoever with the Scott mechanism.

10 The distribution of the water in the Scott valve is also performed in a different manner; in fact, when the scouring and refilling take place 15 the jet supply conduit is entirely cut off, thus preventing the water from going through; in my case, the jet supply conduit is constantly supplied with water, namely both when the scouring as well as the refilling take place. The Scott 20 valve must fit accurately to work, but an accurate fitting is against an apparatus of this kind because if the valve is not operated for a few months, the parts will stick together and if the fitting is too loose, the water leaking through, 25 will prevent the mechanism from giving the desired result.

20 In my case, the piston valve when seated, no metal parts come in contact with one another, and as the fitting is very loose, in fact there is 30 $\frac{1}{8}$ " clearance in the opening of the valve seat, and $\frac{1}{16}$ " clearance in the annular passage controlling the jet in combination with the small piston valve ring, when in all types of piston valves the fitting is very close, only a few thousandths 35 (0.006). This fitting is to prevent the refilling water from being flushed.

35 The foregoing objects and advantages, together with my subsequent features which may be developed in the description, may be best appreciated 40 from a description read in conjunction with the drawings in which:

45 Fig. 1 shows a side view of the bowl and a fragment of the valve, to show the control valve of the jet and shape of the rear of the rim, for the complete drainage to prevent stagnant water 50 from remaining therein, and the hub to hold the nozzle.

50 Fig. 2 is a side elevation of Fig. 1 partly in section.

55 Fig. 3 is a fragmentary elevation partly in section viewed from the left hand side of Fig. 4.

Fig. 4 shows a front view sectioned on line 4-4 of Fig. 3.

Fig. 5 represents a plan view on line 2-2 of Fig. 3.

Fig. 6 is a plan view on line 3-3 of Fig. 4.

Figs. 7, 8, 9, and 10 show a fragment of the valve, housing the piston valve in different phases.

Fig. 11 shows a fragment of the apparatus, 60 showing the operating handle of the valve protruding from the lid of the toilet seat, which is in a raised position.

Fig. 12 shows the lower side of the piston valve which forms part of my invention.

65 The construction of my invention, shown in Figs. 1, 2, 3, 4, 5, 6, 7, 8, 9, 10, 11, and 12 inclusive, is as follows:

70 Fig. 1 shows a wash-down type bowl, all passages therein of suitable size to prevent the flushing water from leaking through the air inlet of the flushing valve, thus working in combination with air inlet of flushing valve 8, showing a fragment thereof, connected to the bowl with spud 9. Control valve 10 for the jet, thus preventing a noisy flushing when the water supply 75

is of very high pressure; 11 water supply jet conduit; 12 the jet nozzle; 13 shows the rear end of the rim suitably shaped to prevent stagnant water from remaining therein as happens in common wash-down bowls, as illustrated in Fig. 2. Of course if the flushing water inlet is located at the side, as shown in Fig. 2, and the flushing valve is not siphon-proof, the water remains stagnant in well 14 Fig. 2, and is subject to being back-siphoned; 15 in Fig. 1 shows a nozzle formed in 10 the rim, for the purpose of wetting the paper.

15 Fig. 2 shows a side view of the apparatus, the flushing valve 8 housing piston valve 16, shown in inoperative position, with plenty clearance 18 and 19 to prevent the valve from sticking. Clearance 18 is $\frac{1}{8}$ " all around, and clearance 19 is $\frac{1}{16}$ " all around; this is plenty to entirely eliminate the possibility of the valve sticking to the valve shell. 20 shows the inlet port for the water supply to the by-pass. 21 are the leather cups; 22 the 20 guiding cone which brings the narrow piston valve 23 into position in the upper stroke of the valve, which controls the jet pressure, more specifically illustrated and described in Figs. 7, 8, 9 and 10. 24 shows the discharge end of the flushing valve; 25 25 a flushing pipe, such as is ordinarily connected to a water closet bowl; 26 the elbow connecting the valve to the bowl in combination with spud 9, such as is also ordinarily connected to a water 30 closet, when located at the back or on top of a bowl, as shown in Fig. 1. 27 shows jet conduit without a control device, which is preferable for pressure not above 80 lbs. The inlet thereof is continually open, therefore, at any time the valve 35 is unseated, the water will enter therein, as more specifically explained in the description of Figs. 7, 8, 9, and 10. 12 shows the nozzle in section. Rim 13 is provided with inclined passages 28, to obtain a whirling action of the water, thus rendering the flushing more efficient. Jet 29 is shown 40 impinging downwardly at the foot of inlet 30 of trap 31, and under the level of the refilling water 32. 33 shows the cover of the flushing valve and 36 the slip-joint nipple.

45 Fig. 3 is a side view of the flushometer, showing front view of handle 34, cover 33, inlet 35 for the water supply, water supply conduit 27 and slip-joint nipple 36.

50 Fig. 4 is a side view in section on line 4-4 of Fig. 3, showing valve shell 8 carrying cover 33, 55 housing piston valve 16. The top thereof, forms no part of this invention, and may be of any suitable automatic type generally used in flushing valves. The lower end is a combination of a valve and guide; 23 is a narrow piston valve controlling the jet, and discharge end 24 is a guide, which, in combination with cone 22 will guide narrow piston valve 23 through annular opening 37. 38 shows the air inlet, free of any check-valve or mechanism for the control thereof, to break the vacuum whenever it occurs in the supply pipeline. The size of this air inlet is the same as that of the internal diameter of the supply pipeline to which the valve is connected, thus allowing enough air to supply the water supply pipeline at any time the vacuum occurs therein, thus eliminating any possibility that any of the contents of the bowl be back-siphoned, as when a small air inlet is used and a sustained intensive 70 vacuum occurs, or, if for any reason, the check-valve or any of the parts fail to work; in case the vacuum occurs in the pipeline, main valve 39 or auxiliary valve 40, or may be both, will open, through which the air will enter the supply pipe- 75

line, thus breaking the vacuum. When the flushing valve works under normal conditions, conduit 41 will convey the exhaust water from dash-pot chamber (A) into the bowl, and the air also, which is continually supplied, into rim 13 of bowl 1, thus the water enters into the bowl promptly and vigorously, which is not the case with an ordinary flushing valve. In addition, this arrangement is noiseless, which is not the case when 10 a vent is used, where the air enters with great velocity, and also in view of the reduced size of the air inlet. 34 shows the operating handle; this also does not form part of my invention as it may be of any type generally employed in flushing 15 valves; 43 is the cover for the chamber of the auxiliary valves; 44 is the guide for said auxiliary valve 40 provided with ports 45 for the exit of the exhaust water from dash-pot chamber (A); 46 is the rubber seat for the auxiliary valve; spring 20 47 keeps rubber seat in position, 48 is a partition suitably placed to prevent exhaust from dash-pot chamber (A) from spilling through air inlet 38, the efficiency and practicability of which was shown in all instances under a very hard test. 25 From this Fig. 4, which is half of the full size, showing the proportion and the shape of the valve, it can be seen that it does not apparently differ from an ordinary valve, but has no similarity with any of the three-cycle flushing valves 30 shown in the above mentioned patents.

By "three-cycle" flushing valves referred to above I mean that type of valve which controls each phase of the flushing of the closet bowl, namely, the scouring by opening communication 35 between the supply line and rim conduit; secondly, it controls the flushing of the bowl by opening communication between the supply line and the flushing jet conduit, and third, the refilling operation by repeating the operation of the first 40 phase. Wherever, therefore, the expression "three-cycle" is used it is intended to describe such an operation as distinguishes from that type of valve which, when operated, releases almost immediately a volume of water into the bowl 45 which scours, flushes and refills, which may be called a "one-action" or "one cycle" type of valve.

Fig. 5 is a plan view of a section on line 2—2 of Fig. 3, showing a fragment of supply pipeline 35, air conduit 41, and a fragment of main valve 39, inlet 20 for supply dash-pot chamber (A) through by-pass 49 more clearly shown in Fig. 4.

Fig. 6 is a plan view on line 3—3 of Fig. 4, 55 showing water supply pipeline 35, air inlet 38, conduit 41 and partition 48, by-pass 49, main valve 39, outlet 50 for the water from dash-pot chamber (A) without showing the auxiliary valve and the guide thereof.

Figs. 7, 8, 9 and 10 show the various working 60 phases of the valve. When handle 34 is operated, the valve will immediately rise from the position, as shown in Fig. 4, and will take a position as shown in Fig. 7; in this rising of the valve, no scouring, flushing or refilling will take place, owing to the great velocity with which it rises; but as soon as operating handle is released, the 65 valve will start slowly on its downward stroke; this speed is regulated by the size of the orifice 70 of the by-pass. It can be seen that annular passage 51 and discharge end 24 of flushing valve 39 will allow the water to accomplish the scouring of the bowl (note also that the water will also enter supply jet conduit 27, but at almost 75 no pressure) as soon as the valve reaches the

position shown in Fig. 8, annular passage 51 will close, thus conveying the water supply into the jet conduit 27, and owing to the small passage thereof, compared to that in annular opening 51, the pressure will rise, according to the static pressure in the supply pipeline, described specifically in Tables (A) and (B) thus obtaining the flushing action for the bowl. 5

Fig. 9 shows the beginning of the refilling action, and the ending of the flushing action, as 10 the water that enters the jet supply conduit will have no pressure from now on, thus preventing flushing of the refilling water for the sealing of the trap.

Fig. 10 shows the reseating of the valve in its 15 original position before it is operated, as shown in Fig. 4.

Fig. 11 shows a fragment of bowl 1 equipped with toilet seat 52 carrying lid 53, shown in a raised position, to show handle 34 protruding 20 from one side of the lid, which permits operation of the valve without the necessity of lowering the lid 53 to find the operating handle of the flushing valve, as is usually the case in all ordinary flushing valves, when connected to the closet in 25 the same position as illustrated in Figs. 1 and 2. To avoid said inconvenience, the seat for closet bowls, equipped with flushing valves, mounted at the center at the rear end of the bowl, do not carry any lid, but for home use the lid is required; one of the reasons being that it can be used as a seat. 30

Fig. 12 shows the details of the lower part of the piston valve formed in three pieces; holder 16, provided with conicity 22 to guide ring valve 35 23 into position for the control of the siphon jet, and kept in position by the threaded extension of discharge end 24 of the flushing valve, screwed into holder 16, thus forming one piece; the other end of the holder is provided with threaded extension 54 to be screwed to piston valve, thus forming one piece therewith. 40

From the foregoing description it will be seen that the purpose of my invention has been accomplished by the device as shown, economically 45 and without complications, and by having reduced to practice said invention, the advantages described herein have proven to be real facts.

Obviously, other forms will readily suggest themselves, it is therefore my intention to include all such forms and modifications of my invention that come within the range and scope of the invention, as expressed in the appended 50 claims.

What I claim as my invention, and desire to 55 secure by Letters Patent, is:

1. A water closet provided with means to drain the water from the rim of said closet, said means including an inclined bottom at the rear end of the rim, thus preventing the water from remaining 60 stagnant in the rim.

2. The combination with a water closet bowl provided with a jet nozzle and having a supply pipe, of a flushing valve discharging the flow of water from said supply to the bowl, a casing for 65 said valve, said casing having an unobstructed air inlet communicating at all times with atmosphere and with the discharge side of said flushing valve whereby back siphoning is prevented, and means for preventing leakage of water 70 through said air inlet.

3. In a water closet having a flushing jet directed into the bowl, the combination of a valve casing provided with a valve seat, a flushing valve 75 cooperating with the seat, means for operating

5 said valve to discharge water therefrom to the flushing jet, and means carried by the valve and cooperating with the casing to cause initial and final flow of water through the flushing jet at relatively low pressure in insufficient amount to flush the bowl, and an intermediate flow through the flushing jet at relatively high pressure to flush the bowl.

4. In a water closet having a flushing jet directed into the bowl, the combination of a valve-casing provided with a valve seat, a flushing valve cooperating with the seat, means for operating said valve to discharge water therefrom to the flushing jet, means carried by 10 the valve and cooperating with the casing to cause initial and final flow of water through the flushing jet at relatively low pressure and an intermediate flow through the flushing jet at relatively high pressure to flush the bowl, said means 15 when in inoperative position being spaced from the casing to prevent freezing thereof to the casing.

5. In a water closet having a flushing jet conduit and a conduit supplying the rim thereof; a 25 water supply pipe, and means for directing the water from the supply pipe simultaneously to both the flushing jet conduit and to the rim conduit, then directing the flow entirely through the flushing jet conduit to flush the bowl, then 30 through both conduits, and finally shutting off the water supply; said means consisting of a flush valve having therein a mechanism actuated by the pressure of the incoming water.

6. In a water closet having a flushing jet conduit and a conduit supplying the rim thereof; a water supply pipe, and means for directing the water from the supply pipe simultaneously to both the flushing jet conduit and to the rim conduit, then directing substantially the entire flow 40 through the flushing jet conduit to flush the bowl, then through both conduits and finally shutting off the water supply; said means consisting of a flush valve, and a piston actuated valve member therein actuated by the pressure of the incoming water.

7. In a water closet having a flushing jet supply conduit and a rim supply conduit; a flush valve having a water inlet, a flushing jet conduit outlet for said valve in open communication with 50 said water inlet throughout the open position of said valve, and means cooperating with said valve during the closing movement of the valve to close communication from the water inlet to the rim supply conduit and to direct the discharge only 55 through one flushing jet supply conduit.

8. In a water closet having a flushing jet conduit and a rim supply conduit, a water supply pipe, and means for directing the flow of water from the said supply pipe simultaneously through 60 said flushing jet conduit and rim supply conduit, said means consisting of a flush valve structure so arranged that during a portion of its open position, the pressure in the flushing jet conduit is greater than during the remainder of its open 65 position.

9. In a water closet having a flushing jet directed into the bowl and a rim having discharge openings therein; a jet conduit connected to the jet, a conduit of larger diameter than the flushing 70 jet conduit connected to the rim, and means for controlling the supply of water to said conduits consisting of a valve casing having a chamber therein, a water supply connection to said chamber, a piston in said chamber, said chamber having 75 a discharge opening, a valve member carried

by said piston cooperating with the discharge opening, a second chamber communicating through said discharge opening in open communication with said flushing jet conduit, a bowl conduit connection for said second chamber, and means for closing said last named connection during a portion of the movement of said piston.

10. In a water closet having a flushing jet conduit and a rim supply conduit connected thereto; means for controlling the flow of water in said conduits comprising, a valve casing having a water inlet discharging into a piston chamber therein, said casing having a distributor chamber having a valve opening communicating with the piston chamber; a valve opening connecting with the rim supply conduit connection; a piston in the piston chamber, a valve member carried by the piston cooperating with the valve opening between the piston chamber and the distributing 15 chamber, and a second valve member carried by the piston, cooperating with the valve opening between the distributor chamber and the rim supply conduit connection, said flush jet conduit being in open communication with the distributor 20 chamber at all times.

11. In a water closet having a flushing jet conduit and a rim supply conduit connected thereto, means for controlling the flow of water to said conduits comprising, a valve casing having a water inlet discharging into the piston chamber therein, said casing having a distributor chamber having a valve opening communicating with the piston chamber and a valve opening 30 connecting with the rim supply conduit connection; a piston in the piston chamber; a valve member carried by the piston cooperating with the valve opening between the piston chamber and the distributor chamber, a second valve member carried by the piston cooperating with the 35 valve opening between the distributor chamber and the rim supply conduit connection, the flushing jet conduit being in open communication with the distributor chamber and means for maintaining open communication from said rim supply conduit connection to the atmosphere; said last named means consisting of an open unobstructed conduit having an internal area at least 40 equal to the area of the water supply pipe.

12. The combination with a water closet bowl 50 provided with a flushing jet nozzle and a rim having discharge openings, a jet conduit connected to the nozzle, a conduit to the bowl, a water supply pipe, and means for successively directing water through both pipes, then directing through 55 the jet conduit connected to the flushing jet nozzle, substantially all the flow and finally through both conduits.

13. In a water closet having a flushing jet directed into the bowl, a valve casing having communication with the flushing jet and bowl through several paths a fluid supply chamber in the valve casing having a single outlet and a valve in said casing, controlling the pressure of flow of water through said outlet to said flushing 60 jet and the flow of water to the bowl.

14. In a water closet including a flushing valve, a casing therefor, a plurality of conduits leading from the casing into the bowl, means for admitting fluid into the shell, and a valve operable to 70 close one of said conduits during a portion of its movement, the other conduit being constantly open.

15. The combination with a water closet bowl, having a flushing jet, of a "three-cycle" flush 75

valve, a casing for said valve having a chamber therein provided with a single discharge opening, said valve including a member passing through said opening and operable by the flushing fluid to control the flow through said discharge opening.

16. In a device of the character described the combination with a water closet bowl provided with a rim having orifices therein and a jet nozzle for discharging fluid into the bowl, a "three-cycle" valve in communication with said orifices and jet, a supply pipe leading to said valve for supplying fluid thereto at pressures up to one hundred pounds, the combined internal areas of the rim orifices and flushing jet being approximately ten times as great as the internal area of said supply pipe, whereby back-building of pressure is prevented.

17. The combination with a water closet bowl provided with a jet nozzle and having a supply pipe of substantially one-half inch standard pipe line, of a flushing valve discharging the flow of water from said supply to the bowl, a casing for said valve, said casing having an unobstructed air inlet communicating at all times with atmosphere and with the discharge side of said flushing valve whereby back siphoning is prevented.

18. The combination with a water closet bowl provided with a jet nozzle and having a supply pipe, of substantially one-half inch standard pipe line, of a flushing valve discharging the flow of water from said supply to the bowl, a casing for said valve, said casing having an unobstructed air inlet at least as large as the inside diameter of the supply pipe communicating at all times with atmosphere and with the discharge side of said flushing valve whereby back siphoning is prevented.

19. The combination with a water closet bowl provided with a jet nozzle and having a supply pipe of substantially one-half inch standard pipe line, of a flushing valve discharging the flow of water from said supply to the bowl, a casing for said valve, said casing having an unobstructed air inlet communicating at all times with atmosphere and with the discharge side of said flushing valve whereby back siphoning is prevented, and means for preventing leakage of water through said air inlet.

20. In a water closet having a flushing jet-conduit and a conduit supplying the rim thereof; a water supply pipe, and means comprising a sleeve-

less piston valve, actuated solely by the pressure of the incoming water, for directing the water from the supply pipe simultaneously to both the flushing jet and to the rim conduit, then entirely through the flushing jet conduit to flush the bowl and finally through both conduits, all during the closing movement of the valve.

21. In a water closet having a flushing jet and a conduit supplying the rim thereof; a valve casing having an inlet chamber formed with a cylinder and a distributing chamber communicating with each other through a single passage; a water inlet communication with said inlet chamber; a jet conduit in open communication with said distributing chamber; the rim conduit having an inlet throat situated in axial alignment with the passage between said chambers; a single piston head in said cylinder; a valve stem on said piston head extending through said chamber connecting passage and said throat; a valve on said stem adapted to seat on the walls of said connecting passage; means operated solely by the incoming water pressure to automatically raise and lower said valve piston; and an enlargement on said stem adapted to pass through said throat and momentarily close said throat whereby the water is directed first into both the rim conduit and the jet conduit, then into the jet conduit alone, and finally into both the rim and jet conduit, all during the closing movement of the valve.

22. In a water closet having a flushing jet directed into the bowl, the combination of a valve casing provided with a seat, a valve cooperating with the seat, means for operating said valve to discharge water therefrom to the flushing jet, and means comprising a stem on said valve having an intermediate enlargement cooperating with a throat in said casing to cause initial and final flow of water through the flushing jet at relatively low pressure in insufficient amount to flush the bowl, and an intermediate flow through the flushing jet at relatively high pressure to flush the bowl, all during a unidirectional movement of the valve.

23. In a water closet having a flushing jet and a conduit supplying fluid to the rim thereof, means for admitting fluid to said jet and rim conduit comprising a piston having a valve carried thereby, said piston and valve being operated by the pressure of the fluid subsequently passing to the flushing jet and rim conduit.
